UNITED STATES PATENT OFFICE.

ELIJAH FAIRBAIRN AND WILLIAM BRAH, OF MILWAUKEE, WISCONSIN,
ASSIGNORS TO THE MILWAUKEE GAS STOVE COMPANY, OF SAME
PLACE.

DESIGN FOR A FIREPLACE-FRONT.

SPECIFICATION forming part of Design No. 25,107, dated January 28, 1896.

Application filed September 23, 1895. Serial No. 563,443. Term of patent 7 years.

To all whom it may concern:

Be it known that we, ELIJAH FAIRBAIRN and WILLIAM BRAH, of Milwaukee, in the county of Milwaukee and State of Wisconsin, have 5 invented and produced a new and original Design for Fireplace-Fronts, of which the following is a description, reference being had to the accompanying drawing, which is a part of this specification.

10 The figure of the drawing is an elevation of a fireplace-front, showing our design.

The leading features of the design are, first, the appearance given to the center of the fireplace-front, whereby the effect of an outwardly-projecting balcony and a canopy overhanging said outwardly-projecting balcony is produced, and, secondly, the ornamental bordering frame shown and described.

15 The lower portion of the center of the fireplace-front is shaped to approximate the form of a balcony, as indicated by the numeral 1. The ends of this balcony extend out from the main body of the frame at obliquities, so that the balcony in reality is projected outwardly 20 from said main body of the fireplace-front. The center of the upper solid portion of the balcony has a lion's head represented thereon, and upon each side of this head the space is filled with ornamental figures, such as clearly 25 shown in the drawing. Below the upper solid portion of the balcony is an open scroll-work 2. The upper canopy effect is indicated by the numeral 3, and like the balcony is shown with forwardly-extending oblique ends 30 in order to project the canopy out from the main body of the fireplace-front, so as to thereby provide for the canopy overhanging

the balcony. The ends of the canopy are suitably ornamented, as shown, and the top ornamented with a palm-leaf, the ends thereof 40 radiating from a shield-like figure. The front strip 4 of the canopy is open-work, in the form of a chain or a series of connected links. Below the canopy is shown a fender, the upright bars 7 of which fender are of substantial S 45 form, and intersecting the entire series of bars is a chain 8. One half of the bars are faced in one direction and the other half in the opposite direction. A curtain 9 is seen as depending from the canopy. The side 50 columns of the bordering frame are each divided into three panels or divisions—viz., a central panel, 9, and the end panels, 10, 10. The latter have represented therein ornamental plates of the shape clearly shown on the drawing. The central panel of each side column is provided centrally with the figure of a shield. Back of the shield are arranged military accoutrements or implements—such as a halberd, simitar, trumpet, &c. The top 60 panel, 11, is shown as provided centrally with a lion's head and upon opposite sides of said head with ornamental scrollwork.

55 What we claim as our invention, and desire to secure by Letters Patent, is—

The design for a fireplace-front as herein shown and described.

In testimony whereof we affix our signatures in presence of two witnesses.

ELIJAH FAIRBAIRN.
WILLIAM BRAH.
